STERILIZING VAPORIZER

Original Filed April 9, 1928

FIG. 3

FIG. 1

John Edward Kenney
INVENTOR
BY *Thompson, Wiley & Son*
ATTORNEY

UNITED STATES PATENT OFFICE.

JOHN EDWARD KENNEY, OF PORTLAND, OREGON, ASSIGNOR TO ELECTRIC VAPO MANUFACTURING CO., OF PORTLAND, OREGON, A CORPORATION OF OREGON.

STERILIZING VAPORIZER.

Application filed April 9, 1928, Serial No. 268,680. Renewed March 26, 1929.

The primary purpose and object of my device is to furnish physicians, hospital attendants, public buildings, operators, home owners, and others with a device to sterilize the air in buildings and elsewhere and make the same palatable, sterile and fit and safe to breathe by releasing within the air of medicated elements from vaporizer in a finely divided state in combination with water vapors so that the medicated elements are held in suspension within the air thereby sterilizing the same.

The invention consists primarily of a body element, electric means for heating the base of the body element and means being provided for dividing the upper portion of the body element into a plurality of compartments, one of which compartments being adapted for the maintaining of water therein, and another of the compartments being adapted for the retaining of the medicated elements therein, and means being provided for the passing of the water vapors when formed by the application of heat through the chamber containing the medicated elements and the final mixing and releasing of the combined vapors through a common outlet into the air.

Means being provided for an easy filling of the various compartments with the respective elements and for the disassembling and the assembling of the completed unit to facilitate the maintaining of the same in a sanitary manner and condition.

Further objects of my new and improved device consist in providing a device of a maximum vaporizing capacity, one that may be easily and quickly heated and that may be maintained in a sanitary and operating condition with little effort, that is neat in appearance and efficient in its operation.

A further object of my new and improved device consists in providing a sterilizing vaporizer that may be safely used by physicians, nurses, hospital attendants, home owners and others through the use of which the spreading of contagious diseases may be halted and prevented.

With these and incidental objects in view the invention consists in certain novel features of construction and combination of

parts, the essential elements of which are set forth in the appended claims, and a preferred form of embodiment of which hereinafter shown with reference to the drawings which accompany and form a part of this specification.

In the drawings:

Fig. 1 is a side elevation of the assembled device.

Fig. 2 is a side elevation, partially in section of the assembled device.

Fig. 3 is a sectional, top, plan view, taken on line 3—3 of Fig. 2, looking in the direction indicated.

Like reference characters refer to like parts throughout the several views.

I preferably form my device of a body element 1, having an outwardly flaring base 2, disposed thereupon terminating in the supporting cylindrical bottom 3. A cross diaphragm 4 is disposed at the lower end of the cylindrical portion of the body element, thus forming a compartment 5, disposed below the diaphragm into which the heating element 6 is placed. Electric current for heating the heating element 6 is supplied through the electric conduit 7, through the base or bottom 3, into the device. To prevent the heating of the bottom structure, an insulated material 8 is placed thereupon and upon which the base rests; an upwardly extending boss 9 rests upon the diaphragm 4 into which a central hollow column 10, is secured as by being threaded thereinto; disposed upon the hollow central column 10 is a band 11, which may be threaded into or made to engage within the top flange 12 of the cup 13. The cup 13 is disposed about the hollow central column 10 and is secured thereto by any suitable fastening means, as by a pressed fit of the flange 14 disposed upon the lower end of the cup 13. A flange or collar 12 is disposed about the upper end of the cup 13 and extends outwardly therefrom, the bottom peripheral surface of which engages the upper end 15 of the body element, the same being made of close fits to prevent the undue escapement of liquids or vapors therethrough. The construction thus illustrated, forms a space 16 which is filled with a carrying agent to be volatilized, as water. Medicated elements are

placed within the space 17 of the cup 13. When heat is applied to the heating element, the temperature rises within the carrying agent, as water, within the compartment 16 5 and the vapors then pass upward through the openings 18 disposed within the collar 12. The water vapors then pass down through the central opening 19 and into the cup 13. The medicated elements disposed within the cup 10 13 are, or should be of such a nature and composition as to volatilize at substantially the same temperature as the carrying agent, as water, disposed within the compartment 16, so that as the vapors pass downward 15 through the central opening 19 of the column 20 the same would enter into the cup 13 and intermingle and mix with the vapors therein developed from the medicated elements. The combined mixed vapors would then pass 20 through the openings 21 disposed through the side walls of the central column 10 and would pass upward therethrough and out into the atmosphere. The carrying agent disposed within the compartment 16 may be placed 25 therein through the filling elbow 22 which is removably secured to the body element 1. A closure cap 23 closes the same. To afford portability to the device and to facilitate the handling of the same while in a heated condition a handle 24 is disposed upon the outside of the body element and is removably secured thereto, the same being preferably made of an insulated material, as wood, or other fibrous material of a slow heating 30 conducting material.

In devices of this kind it is essential that the same be so constructed as to facilitate the maintaining of the same in a sanitary condition. This is accomplished in my new and 40 improved device by the ease with which the same may be disassembled. The cup 25 is in threaded relationship with the outer upper surface of the central column 10 and the conical closure 26 rests upon the upper surface of 45 the collar or flange 12 and extends downward therefrom and the flange 27 disposed upon the lower side engages with the outer surface of the body element. The lower end is in threaded engagement with the boss 9 of the 50 diaphragm 4. The removal of the top structure 25, and the conical closure 26 may then be readily removed from position at which time the central column may be unthreaded from the flange 9 and the cup 13 then removed. The central column being fixedly 55 secured to the cup may then be removed from the cup, so that each of the associated elements may then be thoroughly cleaned and placed in a sanitary condition.

60 While the form of mechanism herein shown and described is admirably adapted to fulfill the objects primarily stated, it is to be understood that it is not intended to confine the invention to the one form of embodiment 65 herein shown and described, as it is suscepti-

ble of embodiment in various forms, all coming within the scope of the claims which follow.

What I claim is:

1. In a device of the class described, the combination of a body element having an outwardly extending base disposed on the lower end of the body element, a diaphragm extending across the body element at the junction of the body element and the base, an electric heating element disposed within the base and below the diaphragm, an electric conductor for supplying heating energy to the heating element, an upward extending boss disposed central of the diaphragm and removably secured thereto, a cup disposed the ends of the central column, said cup having an outwardly extending annular top flange adapted to engage with and rest upon the upper end of the body element, a band disposed about the central column and in registerable alignment with the cup and adapted for engagement with the cup and to form a tight fitting lid therefor, a plurality of openings disposed within the top flange and a plurality of hollow columns upwardly extending from the band and extending therethrough, a conical closure disposed about the central column and resting upon the top flange and adjustable means for maintaining the assembled unit in adjustment and assembled.

2. In a device of the class described, the combination of a body element having a base disposed its lower end and a diaphragm disposed its ends to form two compartments, one on either side of the diaphragm, a heating element disposed adjacent to and below the diaphragm, means for supplying heat associated with the heat element, a central hollow column upwardly extending from the diaphragm and removably secured thereto, a cup secured to the central column and disposed within the upper compartment of the body element, a closure for the body element and removably secured thereto about the central column which upwardly extends therethrough, intercommunicating passageways disposed between the upper compartments disposed within the body element and means for filling the upper compartment disposed within the body element and for exhausting the vapors developed within the body element and within the cup.

3. In a device of the class described, the combination of a body element composed of side walls and a horizontal diaphragm dividing the body element into compartments, one of said compartments having means associated therewith for the application of heat to the diaphragm and the other of the compartments comprising a liquid holding well, a second liquid holding compartment disposed within one of the compartments of the body element and a third compartment form-

ed by a closure removably secured to the upper end of the body element and intercommunicating passageways connecting the compartments and the exterior through the removable closure of the body element.

4. In a device of the class described, the combination of a body element, compartments disposed within the body element and means for supplying heat through the bot-

tom to one of said compartments, a hollow column removably secured to the bottom of the body element and upwardly extending through the compartments disposed within the body element, and intercommunicating passageways connecting the compartments and the hollow column to the exterior.

JOHN EDWARD KENNEY.
